CLAIM

We claim, the ornamental design for an operating/display panel, as shown and described.

DESCRIPTION

FIG. 1 is a perspective view of an operating/display panel, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another perspective view thereof, as shown mounted to a wall in a user environment; and,

FIG. 9 is another side view thereof, as shown mounted to a wall in a user environment.

The jagged broken lines shown in FIGS. 8 and 9 represent break lines. The broken lines in FIGS. 8 and 9 showing wall features illustrate environmental structure. All other broken
